MUFFLER

Benjamin Leslie Vipond, Kensington, Md.

Application July 1, 1933, Serial No. 678,637

8 Claims. (Cl. 137—160)

My invention relates to improvements in mufflers for the exhausts of internal combustion engines or the like.

An important object of my invention is the provision of a muffler which will effectively silence the exhaust without setting up any appreciable back pressure on the motor or the like.

A further object of my invention is the provision of a muffler which is of simple and durable construction and which does not have parts subject to wear and breakage, such as the baffles in use in many mufflers.

Other objects and advantages of my invention will be apparent during the course of the following description.

In the accompanying drawing which forms a part of this specification and wherein like characters of reference denote like parts throughout the same,

Figure 1 is a longitudinal sectional view of a muffler embodying my invention,

Figure 2 is a transverse section through the inlet end thereof,

Figure 3 is a transverse section through a muffler formed in two parts.

Figure 4 is a fragmentary longitudinal section of a modified form of muffler, and,

Figure 5 is a longitudinal section of a still further modified form of muffler.

In the drawing, wherein for the purpose of illustration is shown a preferred embodiment of my invention, the numeral 10 designates the muffler casing which is substantially conical in shape and is open at its small discharge end which opens into the usual tail pipe 11. The large inlet end of the muffler casing is closed and is preferably dished inwardly as seen at 12 in Figure 1. The exhaust pipe 13 enters the muffler casing tangentially immediately adjacent the closed end 12

and discharges the exhaust gases against the side of the casing. The inwardly dished end of the casing forces the gases to follow the casing in a whirling path, as shown by the arrows in Figure 2 and also prevents the drumming sound which would be set up by the exhaust gases causing vibration of the end of the casing were it not dished. This drumming sound can also be prevented by dishing the casing end outwardly as shown by dotted lines in Figure 1.

The muffler casing is provided with a series of spaced circumferential grooves 14 arranged at intervals and throughout the length of the casing. Each successive groove is of less diameter approaching the discharge end of the casing due to the tapering of the casing. The portions of

the casing between the grooves 14 taper toward the discharge end of the tube and are preferably, but not necessarily, dished inwardly as indicated at 15 in Figure 1. The grooves 14 therefore divide the casing into a series of successive substantially frusto-conical sections connected with the smaller end of each section merging into the larger end of the next adjacent section in the direction of the discharge end of the casing, to form a curved shoulder 16 in front of each groove.

The grooves 14, shoulders 16 and connecting portions 15 are curved to merge into one another thereby producing a muffler casing having a smooth wave like contour with no abrupt turns or shoulders.

In operation, the exhaust gases enter the large end of the muffler casing through the tangentially disposed exhaust pipe 13 and impinge against the wall of the casing. The wall of the casing and the bulged end wall 12 cause the gases to assume a whirling or substantially circular path around the casing, and this whirling path gradually decreases in diameter, with successive increases in diameter, as the gas approaches the discharge end of the muffler. This whirling motion of the gases together with the rolling of the gases over the rounded ridges and grooves of the casing neutralizes the sound waves and thoroughly silences the exhaust gases without setting up any appreciable back pressure.

The casing may be formed in any convenient manner. For convenience of manufacture the muffler casing may be formed in two half sections with the joints overlapped and welded together as shown in Figure 3. With this construction the gases pass over the telescoping joints without interference, as indicated by the arrows in Figure 3.

In place of the parallel spaced grooves 14 the muffler casing may be provided with a continuous spiral or helical groove 17 as seen in Figure 4, which further contributes to the whirling motion of the gases. The casing of Figure 4 is otherwise formed as in Figure 1.

If desired the grooves may be dispensed with and a plain substantially cone shaped casing provided as in Figure 5. In this form of my invention the tangentially disposed exhaust pipe 13 and the inwardly bulged inlet end wall 12 are relied upon to produce the whirling of the gases through the casing.

While I have shown and described the preferred embodiment of my invention, it is to be understood that various changes in the size, shape and

arrangement of parts may be resorted to without departing from the spirit of my invention or the scope of the subjoined claims.

Having thus described my invention, what I claim and desire to protect by Letters Patent is:

1. A muffler comprising a substantially conical casing having a discharge opening at its smaller end, and an inlet pipe extending tangentially through the casing wall at the larger end thereof, said casing having circumferential grooves spaced along its length.

2. A muffler comprising a substantially conical shell having a discharge opening at its smaller end, and an inlet pipe extending tangentially through the casing wall at the larger end thereof, said casing having a helical circumferential groove extending longitudinally thereof.

3. A muffler comprising a substantially conical casing having a discharge opening at its smaller end, an inwardly bulged end wall closing the larger end of the casing, and an inlet pipe extending tangentially through the casing wall adjacent the bulged end wall thereof, said casing having circumferential grooves spaced along its length.

4. A muffler comprising a substantially conical casing having a discharge opening at its smaller end, an inwardly bulged end wall closing the larger end of the casing, and an inlet pipe extending tangentially through the casing wall adjacent the bulged end wall thereof, said casing being provided with a helical circumferential groove extending longitudinally thereof.

5. A muffler comprising a substantially conical casing having a discharge opening at its smaller end, and an inlet pipe extending tangentially through the casing wall at the larger end thereof, said casing having a series of spaced circumferential grooves and rounded shoulders merging into each groove at the inlet side thereof, whereby the casing is divided into a series of connected

substantially frusto-conical sections, the smaller discharge end of each section opening into the larger inlet end of the next adjacent section.

6. A muffler comprising a substantially conical casing having a discharge opening at its smaller end, an inlet pipe extending tangentially through the casing wall at the larger end thereof, said casing having a series of spaced circumferential grooves and rounded shoulders merging into each groove at the inlet side thereof, whereby the casing is divided into a series of connected substantially frusto-conical sections, the smaller discharge end of each section opening into the larger inlet end of the next adjacent section, and an inwardly bulged end wall at the larger end of the casing.

7. A muffler comprising a substantially conical casing having a discharge opening at its smaller end, an inwardly bulged end wall closing the larger end of the casing, an inlet pipe extending tangentially through the casing wall adjacent the bulged end wall thereof, said casing being provided with a helical circumferential groove extending longitudinally thereof, and a helical rounded shoulder merging into said groove throughout its length on the inlet side thereof.

8. A muffler comprising a substantially conical casing having a discharge opening at its smaller end, an inwardly bulged end wall closing the large end of the casing, and an inlet pipe extending tangentially through the peripheral wall of the casing at its intersection with the inwardly bulged end wall whereby gas passing through said inlet pipe will be discharged between the bulged portion of the casing end wall and the peripheral wall of the casing, said casing being grooved to provide in longitudinal cross section a series of restricted portions gradually merging into the other portions of the casing by means of rounded surfaces.
